Frank S. Bauer
ATTORNEY.

UNITED STATES PATENT OFFICE.

JOSEPH BREZIN, OF PHILADELPHIA, PENNSYLVANIA, ASSIGNOR, BY DIRECT AND MESNE ASSIGNMENTS, TO NATIONAL METAL STAMPING COMPANY, A CORPORATION OF PENNSYLVANIA.

BAG FASTENER.

Application filed October 24, 1923. Serial No. 670,411.

To all whom it may concern:

Be it known that I, JOSEPH BREZIN, a citizen of the United States, residing at Philadelphia, county of Philadelphia, and 5 State of Pennsylvania, have invented a new and useful Improvement in Bag Fasteners, of which the following is a full, clear, and exact description, reference being had to the accompanying drawings, which form a part 10 of this specification.

My invention relates to bag fasteners as, for example, such as are used on traveling bags for securing the overlapping frame sections together.

15 The object of my invention is to provide an improved fastener so constructed as to be efficient in operation and at the same time comprising a minimum number of parts, which may be readily and inexpensively 20 made, and which may be easily assembled without the use of tools.

Further objects of my invention are to provide an improved fastener which will be attractive in appearance, easily operated 25 and proof against derangement of its parts and consequent failure in operation.

The bag fastener in accordance with my 30 invention is of the general type, but an improvement on the fastener disclosed in an application for patent filed by myself and Louis Berzon, Serial No. 484,533, filed July 14, 1921.

Having now indicated, in a general way, the nature, purpose and advantage of my 35 invention, I will proceed to a detailed description thereof, with reference to the accompanying drawings in which is illustrated a preferred embodiment, and in which—

Fig. 1 is a fragmentary view of a bag 40 frame with a fastener embodying my invention in position.

Fig. 2 is a view, partly in section, of a fastener embodying my invention.

Fig. 3 is a perspective view of the bolt 45 and carrying plate.

Fig. 4 is a perspective view of a retainer plate.

Fig. 5 is a perspective view of a spring plate.

50 Fig. 6 is a plan view of the retainer plate and spring plate assembled.

a represents a bag frame member adapted, when the bag is closed, to overlap a similar

member and be secured thereto. *b* represents a casing of brass, or any suitable material, secured to the frame member *a* by means of lugs *c*, which extend through suitable apertures in the frame and are bent over against the underside of the frame, as shown. In the top of the casing is centrally located a longitudinally extending slot *d* and adjacent one end is located a transverse slot *e*, the top of the casing being raised adjacent the ends of the transverse slot to form lugs *f*, *f*. 55

The curved bolt member *g* is provided at one end with a hook *h* and is secured at its other end to the underside of a bolt carrying plate *i*, one end of which is provided with an extension bent around to form a hook *j* 70 and provided on its outer surface with a lug or protuberance *k*. The hooked end of the bolt is adapted to engage with receiving means carried by the frame member of the bag overlapped by member *a*. 75

The retainer plate *l* has its end portions offset or bent out of line at its ends, as shown in Fig. 4, and is provided adjacent each end with slots *m* and *n*. A slot *o* is provided intermediate the slots *m* and *n* and connected 80 by slot *p* with the slot *m*.

The spring plate *q* is provided adjacent one of its ends with a longitudinally extending slot *r*.

To assemble the fastener, the bolt *g* is 85 passed downwardly through the slot *d* in the top of the casing and the bolt carrying plate *i* positioned on the top of the casing with hooked extension *j* extending through slot *e* and lying between lugs *f*, *f*. 90

The retainer plate *l* is placed within the casing beneath the top in such a manner that the bolt will pass through the slot *p* and the hook *j* of the bolt carrying plate will pass 95 through slots *n* and *o* and engage the portion of the retainer plate between the slots. The spring plate *q* is then placed in the casing beneath the retainer plate in such a manner that the bolt will pass through the slot *r* and the ends of the spring are passed

100 through slots *m* and *n* in the retainer plate and bear against the inside of the ends of the casing. The spring will then bear against the lug *k* on the hooked extension of the bolt carrying plate and be flexed. 105

It will be observed that the bolt carry-

ing plate lying outside the casing is secured by the engagement of the hook *j* with the retainer plate and that it may be raised and lowered, pivotally on the retainer plate, in order to move the bolt to locked or unlocked position. Side movement of the plate *i* is prevented by lugs *f*, *f*.

The retainer plate is secured in the casing by the spring, the end portions which pass through the slots *m* and *n* and engage the plate and the inside of the end walls of the casing. The spring is flexed and its ends forced against the casing by engagement of the spring with the lug *h* on hook *j*. It will thus be seen that the spring plate performs the dual function of securing the retainer plate, by frictional engagement with the plate and casing, thus avoiding the necessity of riveting, and of yieldingly retaining the bolt in locked and unlocked position.

Having now fully described my invention, what I claim and desire to protect by Letters Patent is:

1. A bag fastener comprising a casing having openings therethrough, a locking bolt extending through one of the openings in the casing and a pivotal member also extending into the casing, a retainer plate in the casing, there being a pivotal connection between the bolt and retainer plate, and a spring plate interlocked at both ends with the retainer plate and engaging the pivotal member of the bolt intermediate its ends for retaining the parts in their assembled relation.

2. A bag fastener comprising a casing, a bolt retainer in the casing, a bolt pivotally connected to the retainer and a spring in the casing bearing on the retainer at both ends and on the pivotal connection between the bolt and the retainer between its ends to retain the retainer and bolt in their assembled relation.

3. A bag fastener comprising a casing, a bolt retainer plate in the casing, a bolt pivotally connected to the retainer plate and a spring in the casing bearing on the retainer plate at both ends and on the pivotal connection between the bolt and the retainer plate between its ends to retain the retainer plate and bolt in their assembled relation, said retainer plate being engaged by the casing and bag frame when the fastener is

secured to the bag frame to secure the parts in the casing.

4. A bag fastener comprising a casing, a bolt retainer in the casing having three cross bars, a bolt having a hook pivotally engaging the intermediate cross-bar, a leaf spring extending over the two end cross-bars and under the hook of the bolt and the intermediate cross-bar to retain the parts in their assembled relation, and means on the hook on the bolt in engagement with the spring for retaining the bolt in its open and closed positions.

5. A bag fastener comprising a casing having openings in the top, a bolt carrying plate adapted to overlie the casing, one end of said plate being hooked and extended within the casing, a bolt carried by said plate, a retainer plate within the casing provided with slots adjacent its ends, adapted to engage the hooked end of said bolt carrying plate, and a spring plate adapted to bear on the hooked end of said bolt carrying plate to yieldingly retain the bolt in locked or unlocked position and to pass through said slots in the retainer plate and frictionally engage the casing to secure said plate within the casing.

6. A bag fastener comprising a casing having openings in the top, a bolt carrying plate adapted to overlie the casing, one end of said plate being hooked and extended within the casing, a bolt carried by said plate, a retainer plate within the casing, slotted for the passage of the bolt and the end portions of which are offset and provided with slots, adapted to engage the hooked end of said bolt carrying plate, and a spring plate slotted for the passage of the bolt, the ends of which are adapted to pass through said slots in said retainer plate and engage the end walls of said casing, said spring intermediate its ends engaging the hooked end of said bolt carrying plate and being flexed thereby, forcing its ends against the end walls of the casing whereby the retainer plate is secured within the casing and the bolt will be yieldingly retained in locked or unlocked position.

In testimony of which invention, I have hereunto set my hand, at Philadelphia, Pa., on this 22nd day of October, 1923.

JOSEPH BREZIN.
